UNITED STATES PATENT OFFICE.

SAMUEL KOPS, OF NEW YORK, N. Y.

ABDOMINAL STRAP FOR APPAREL-CORSETS.

No. 892,742.

Specification of Letters Patent.

Patented July 7, 1908.

Application filed January 3, 1908. Serial No. 409,119.

To all whom it may concern:

Be it known that I, SAMUEL KOPS, a citizen of the United States, residing at the borough of Manhattan, city, county, and 5 State of New York, have invented an Improvement in Abdominal Straps for Apparel-Corsets, of which the following is a specification.

My invention relates to an improvement in 10 abdominal straps of apparel corsets such as shown and described in Letters Patent #593,397, #610,063, #694,161, #798,967 and #824,490, granted to my brother Daniel Kops, which devices are manufactured by 15 the firm of Kops Bros., of which we are members. By reference to any one or more of these patents it will be noticed that the abdominal flaps in said patents are provided with eyelets at their free ends arranged in 20 series and that posts are attached to one or both of the steels of the apparel corset; these eyelets being engaged with the post or posts for connecting the abdominal straps to apply a supporting tension at the lower portion of 25 the corset. It has been found in practice that these eyelets are liable in use to pull away from the fabric. In fact, being placed close together the strain on the fabric especially by any one of the eyelets but the one 30 nearest the free end is liable to pull the same away from the fabric as the main support is the intervening fabric, and the object of my invention which applies especially to these eyelets is to obviate this difficulty.

35 In carrying out my invention and in an effort to cause the eyelets to hold alike on both sides and any one of the eyelets to be in a measure supported by the rest, I provide a plate washer having a series of openings receiving the ends of a series of eyelets and which ends are to be over-turned against the outer surface of the plate as they clamp the goods and are held thereto; the plate being forced against the goods on one side with the 45 bases of the eyelets on the other side. This plate may be of any shape or form and the eyelets arranged in a group of any corresponding shape or form, and while I do not limit myself in this particular, I prefer in the 50 device illustrated in connection herewith to employ the series of eyelets in line, and I further prefer to arrange and form a series of eyelets from a single plate corresponding with the plate washer and coming at the opposite side of the goods so that the fabric is held by the eyelets between the two plates

and is gripped between the plates so that when the post or posts of the steels engage with one of the series of eyelets the remaining washers and plates lend their support of 60 the grip of the fabric to the eyelet engaged so that the strain or tension applied to the straps of the corset is not as heretofore carried by one of the eyelets but by the group composed of the plates and eyelets. 65

In the drawing, Figure 1 is an elevation representing the lower portion of my apparel corset and the device of my invention as applied to the abdominal flaps of the corset, one flap being shown in position and the other out-turned. Fig. 2 is an elevation in large size of the free end of one of the abdominal flaps. Fig. 3 is a longitudinal section at *x*, *x*, Figs. 2 and Fig. 4 is a longitudinal section on the same line showing a modified form of the invention.

The form of corset shown in Fig. 1 agrees substantially with that shown in the before named Letters Patent #824,490 simply for the purpose of illustration, and in which *a* represents the fabric body, *b* *b*¹ gores at the lower front portion of the same and *c* *c* steels at the opposite sides of the front. The flaps *d* *e* are shown with hose supporter skirts *d*¹ *e*¹ although of course my invention has no particular reference to this structure. These flaps are sewed to the distant edges of the corset gores along the sewed lines of union 2 3. The front steels are provided at the desired point with posts 4 5 and the free ends of 25 the abdominal flaps *d* *e* with series of eyelets of any desired number adapted to engage these posts in connecting and applying tension to the same in use. These eyelet devices as illustrated in Figs. 1, 2 and 3, each 30 comprise a washer plate *f* coming against the outer surface of the fabric of the flaps *d* *e* which washer plate as shown is provided with 35 three holes.

The eyelets *h* are formed from a plate *h*¹ by 40 the drawing operation well known in the metal working art. The eyelets are spaced apart and as shown are three in number. The plate *h*¹ agrees in shape and in dimensions with the plate *f* and while the plate *f* 45 comes on the outside of the fabric or flaps the plate *h*¹ comes on the inside, the eyelets passing through the fabric of the flaps through the holes in the washer plate with the free edges of the eyelets forcibly over-turned 50 against the outer surface of the plate *f*. In 55 this manner the fabric of the flaps is gripped

between the two flat surfaces of the plates f and h^1 and the entire amount of fabric so gripped and which agrees with the dimensions of the plates contributes to the support of the 5 tension applied to the fabric at the end of the flaps when any one of the several eyelets of the series is brought into engagement with either post 4 or 5 instead of depending upon any one of the eyelets of the series to support 10 this tension. In this manner the structure is stiffened and strengthened and the useful life of the free ends of the abdominal flaps prolonged.

The forms of my invention shown respectively by the sections Figs. 3 and 4, are alike in the employment of a washer plate f and series of eyelets h and only differ in the fact that in Fig. 3 the series of eyelets are formed integrally with the eyelet plate h^1 coming on 15 the opposite side of the fabric to the washer plate f , whereas in the form shown in Fig. 4, the eyelets h are separate and provided with broad bases h^2 which almost come into contact with one another upon the opposite side 20 of the fabric of the flaps to the side occupied 25 by the plate f .

The structure in Fig. 4 performs almost identically the function of the structure shown in Fig. 3 because of the broad bases to 30 the eyelets and the fact that they are all connected to a common or unitary washer plate f lending the united support of the series of eyelets to the tension applied to any one eye, and while I have shown this form of my invention in Fig. 4, I do not attach quite as 35 much importance to it as to the forms shown in Figs. 1, 2 and 3. The device of my invention is especially adapted for use in corsets and other undergarments or articles of apparel where there is considerable strain applied to one or more of the group of eyelets. 40

I claim as my invention:—

1. The combination with an article of apparel and a series of eyelets passing through 45 the same in a juxtaposed relation, of a unitary or common washer plate of thin metal coming against the outer surface of the fabric and perforated to receive the free and smaller ends of the eyelets and against which said 50 ends are over-turned.

2. The combination with an article of apparel and a series of eyelets passing through the same in a juxtaposed relation, of a uni-

tary or common washer plate perforated to receive the free and smaller ends of the eyelets and against which said ends are over-turned, and a plate coming at the opposite side of the fabric to that occupied by the washer plate and with which said series of eyelets are integrally formed. 55

3. The combination with an apparel corset, the abdominal flaps of the same and one or more posts secured to the corset steels, of series of eyelets extending through the fabric at the free ends of the abdominal flaps, 60 and a washer plate of thin metal coming against the outer surface of the flaps of the fabric and receiving the free ends of said eyelets and against which plate said free ends are over-turned. 70

4. The combination with an apparel corset, the abdominal flaps of the same and one or more posts secured to the corset steels, of series of eyelets extending through the fabric at the free ends of the abdominal flaps, a 75 washer plate coming against the outer surface of the flaps of the fabric and receiving the free ends of said eyelets and against which plate said free ends are over-turned, and a second plate with which the eyelets of 80 said series are integrally formed, the latter plate coming against the opposite side of the flap fabric and gripping the same between the two plates, the gripping support of the plates being bent to the eyelets with the tension applied in connecting the flaps to their posts. 85

5. The combination with a unitary or common washer plate of elongated rectangular form having a series of apertures therein in line, of a plate of similar form and an integral 90 series of eyelets formed therefrom, the axial centers of which agree with the centers of the apertures of the washer plate, a garment and a part connected therewith along one line of 95 sewing and to the free end of which said series of eyelets, the integral plate thereof and the washer plate are connected in a binding relation and a device connected to the garment adapted to be engaged by any one of the eyelets of the series. 100

Signed by me this 30th day of December 1907.

SAMUEL KOPS.
